CLAIM

The ornamental design for a hub cap vent plug, as shown and described.

DESCRIPTION

FIG. 1 is a front perspective view of a hub cap vent plug showing one embodiment of our new design.

FIG. 2 is a front elevational view of the embodiment of FIG. 1.

FIG. 3 is a rear elevational view of the embodiment of FIG. 1.

FIG. 4 is a right side view of the embodiment of FIG. 1.

FIG. 5 is a left side view of the embodiment of FIG. 1.

FIG. 6 is a top plan view of the embodiment of FIG. 1.

FIG. 7 is a bottom plan view of the embodiment of FIG. 1.

FIG. 8 is a cross-section view of the embodiment of FIG. 1.

FIG. 9 is a front perspective view of a hub cap vent plug showing another embodiment of our new design.

FIG. 10 is a front elevational view of the embodiment of FIG. 9.

FIG. 11 is a rear elevational view of the embodiment of FIG. 9.

FIG. 12 is a right side view of the embodiment of FIG. 9.

FIG. 13 is a left side view of the embodiment of FIG. 9.

FIG. 14 is a top plan view of the embodiment of FIG. 9.

FIG. 15 is a bottom plan view of the embodiment of FIG. 9.

FIG. 16 is a cross-section view of the embodiment of FIG. 9; and,

FIG. 17 shows how a vent plug having a new design as disclosed herein may be disposed relative to vehicle hub cap. In the drawings, the broken lines depict environmental subject matter only and form no part of the claim.

1 Claim, 13 Drawing Sheets
